UNITED STATES PATENT OFFICE.

ELIZABETH A. KRATZ, OF JOHNSTOWN, NEW YORK.

CONVERTIBLE SEAT FOR CHILDREN.

Application filed September 26, 1921. Serial No. 503,167.

To all whom it may concern:

Be it known that I, ELIZABETH A. KRATZ, a citizen of the United States, residing at Johnstown, in the county of Fulton and 5 State of New York, have invented certain new and useful Improvements in Convertible Seats for Children, of which the following is a specification:

My invention relates to a convertible and 10 portable seat for small children. The main object of the invention is to provide a seat of this character that can be suspended from the sides of a bath tub in order to enable the child to be left unattended therein without 15 danger so that it may play and splash around in the water.

Another object of the invention is to provide suitable attachments for the seat so that it may be stood on the ground instead of 20 suspended in the bath tub and in that manner used as an ordinary outing seat.

Still another object of the invention consists in constructing the seat so that it may be portable and collapsed into very small 25 dimensions.

In the accompanying drawing one embodiment of the device has been illustrated, and

Figure 1 shows a perspective view of the 30 baby seat as suspended from the sides of a tub;

Figure 2 is also a perspective view which shows the seat standing on the floor;

Figure 3 shows the attaching means in 35 detail; and

Figure 4 is a plan view of a portion of Figure 3.

The seat proper is denoted by the numeral 10 and is constructed somewhat in the shape 40 of a bicycle seat. It is provided with a number of small studs 11 around its outer edge for the purpose of attaching it to straps 12 which are secured to coiled tension springs 13 which in turn are hung on hooks 14 secured in a wooden frame or guard 15. The 45 straps 12 are provided with a number of button holes 16 so that the seat may be raised or lowered in accordance with the size of the child.

50 The guard or frame 15 is circular and big enough to accommodate the body of a child in its opening.

55 Four brackets 17 are secured on the flat underside of the frame 15 by means of screws or other suitable attaching members. As seen in Figure 3 these brackets are of

angular shape with a horizontal portion 18 and a vertical portion 19 and are attached near the outer edge of the frame or guard 15. In the vertical portion 19 of the bracket 60 is shown a small hole to accommodate the short finger 20 of one end of the suspension member 21. Each member is provided with two comparatively long side shanks and a connecting piece 22. These suspension members which are two in number are furthermore bent to form open hooks 23 at the top, shaped to engage the rim of a bath tub and the hooks 23 are preferably covered with a short piece of rubber hose to give a good 70 grip to the edge of the bath tub. A notch 35 is provided on finger 20 to prevent it from slipping out of bracket 17.

The two shanks 21 have each a short bend 24 near the lower end which bend engages 75 with the edge of the frame 15 when the members are attached thereto, and the fingers 20 are bent toward each other so as to give a good grip in the holes in their corresponding brackets 17. In order to engage 80 in these holes the shanks have to be sprung apart slightly to slip over the vertical portions of the brackets. These brackets are positioned on the sides of the frame 15 in such a manner that the two connecting portions 85 22 of the suspension members become parallel with each other and with the fingers 20 at the lower end of the members, when the latter are in position on the frame 15.

In Figure 2, the device is shown as stood 90 on the ground after the suspension members have been detached. For this purpose the stand is constructed with two legs 25 which are made out of a bent piece of wire, the free ends or points 26 of which are intended to 95 engage with the holes 27 in the vertical portion of the bracket 17. An abutment piece 28 consisting of a short piece of wire running cross wise near the end of the legs 25 is provided to abut against the horizontal 100 portion 18 of the bracket 17. In order to give sufficient hold in the frame 15, a socket 29 is provided therein and consists of a hole drilled in continuation of the hole 27 in the bracket.

105 The two legs 25 are connected by means of rods 30 engaging their cross pieces 31 which are slightly raised above the floor line for the purpose that the corners 32 may form feet of the legs. It should be noted 110 that the legs are not standing perpendicular when in position, but are bent apart

to form a wide base of the stand. The feet 32 on each leg are furthermore wider apart than the points 26, or in other words the shanks of the legs are closer together near 5 the frame than at the floor. Stops 33 prevent the rods 30 from sliding on cross pieces 31.

It will readily be seen that by detaching both legs 25 and folding them together, and 10 also detaching the suspension members 21 and placing them together with the legs 25 flat against the frame 15, a very compact package can be formed, making the device portable.

15 When the device is applied to a bath tub, the height of the seat 10 is adjusted by means of straps 12 and studs 11 in accordance with the size of the child so that the proper distance is attained between the 20 top of the seat and the frame 15. The suspension members 21 are now attached to the vertical portion 19 of the brackets by springing the shanks of the members apart sufficiently to pass over the sides of the 25 brackets, whereupon the shanks will again spring together, thus making a secure connection between the frame 15 and the suspension members. The latter are now hung with their hooks over the rim of the bath 30 tub and the child can be placed in the seat and the tub filled to a proper height for the child to play in. In this manner the child may splash about in the water to its heart's content which affords excellent physical exercise under very healthy conditions.

35 In using the device as an "outing seat" the suspension members 21 are detached from the frame 15 and replaced by the stand by slipping the ends of the legs 25 into their 40 sockets in brackets 17. In the latter case the child can be left unattended as it is impossible for it to fall out of the device.

Having thus described the invention what is claimed as new is:

1. In a bathing seat for a child, a seat 45 member, a guard and flexible means on the under side of said guard to which said seat member is attached, a plurality of L-shaped brackets on the under side of said guard arranged in pairs near its edge and provided 50 with horizontal apertures, flexibly connected rods constituting hooks adapted to engage with parallel rail members, the free ends of said hooks being provided with nicked opposing fingers adapted to engage with 55 the horizontal apertures in said brackets, the flexible connection of said hooks tending to draw said fingers together.

2. In a combination seat for a child, a seat member, a guard and flexible means on 60 the under side of said guard to which said seat member is attached, a plurality of L-shaped brackets on the under side of said guard arranged in pairs near its edge and provided with horizontal and vertical apertures, flexibly connected rods constituting 65 hooks adapted to engage with parallel rail members, the free ends of said hooks being provided with nicked opposing fingers adapted to rigidly engage with the horizontal apertures in said brackets, the flexible connection of said hooks tending to draw said fingers together, legs each comprising a horizontal bar flexibly connecting 70 upright rods adapted to engage in the vertical apertures in said brackets and a detachable cross connection between the horizontal bars of said legs, whereby said seat 75 may be used selectively as a bathing seat or a stand by substitution of the legs for said suspension members.

In testimony whereof I affix my signature.

ELIZABETH A. KRATZ. [L.s.]
